UNITED STATES PATENT OFFICE.

ELMER L. OGLE, OF CHICAGO, ILLINOIS, ASSIGNOR TO FEDERAL ELECTRIC COMPANY, OF CHICAGO, ILLINOIS, A CORPORATION OF ILLINOIS.

ELECTRIC FUSE.

Application filed October 27, 1921. Serial No. 510,826.

The invention relates to improvements in electric fuses and consists of the matters hereinafter described and more particularly pointed out in the appended claims.

5 The object of the invention is to simplify and improve the construction of electric fuses, more especially those designed for heavy loads, whereby they are made more ready of assembly and more easily flexible 10 in the matter of adjustment of the cartridge to the designed load.

The advantages of the improved fuse will appear as I proceed with my specification.

In the drawings:—

15 Figure 1 is a view representing the improved fuse in side elevation;

Figure 2 is a view on a large scale, representing a longitudinal central section through the fuse;

20 Figures 3, 4 and 5 are sectional views in planes indicated respectively by the lines 3—3, 4—4, and 5—5 of Figure 2;

Figure 6 is an end view of the fuse, showing the end with the fixed head;

25 Figure 7 is a perspective view of the fusible bars of the cartridge and their means of support;

Figure 8 is a perspective view of the removable head of the fuse;

30 Figure 9 is a perspective view of an end of the fuse showing a modified form of the removable head.

Referring now to that embodiment of the invention illustrated in the drawings:—10 35 indicates the body of the fuse, which is of the knife-blade contact type, and 11, 12 indicate the contact blades. 13 indicates the enclosed cartridge which contains the fusible member. The body is a heavy tube of 40 insulating material, such as fibre or the like and is closed at its ends by metallic, tubular heads 14, 15 which carry the blades 11 and 12 respectively.

45 The one head 15 is permanently attached to the tube 10. The tubular part of the head closely embraces the end of the fibre tube 10, with its flat head engaged against a flat metal disc 16, which in turn engages against the end of the tube 10 and 50 the head is fixed on the tube by means of rivets 17. The blade 12 extends through a slot in the flat head and has spaced extensions 12^a, 12^b which extend through holes in the disc 16 and are riveted against the inner face of said disc.

The other head 14 is made in two separable parts, (see Figures 2, 3 and 8), namely a short tube 18, which is permanently attached to the fibre tube by rivets 18^a and inner and outer flat discs 19, 20, which are 60 attached together and secured to the associated blade 11 by means of spaced rivet extensions 11^a, 11^b on said blade and which fit snugly within the open end of the metal tube 18 and against the end of the fibre tube 65 10, beyond which said metal tube extends a distance equal to the thickness of the two discs. The outer disc 20 has diametrically opposed ears 21, 21 which extend at right angles to the plane of the disc and embrace 70 the tube 18 and are secured thereto by screws 21^a—the metal of the tube being upset through the fibre tube 10 and tapped to receive said screws. The projecting end of the tube 18 is notched to receive the radial 75 disc extensions 21^b of which the ears 21 are parts and the projecting part of the tube is bent adjacent said notches to provide pairs of spaced lugs 22 which engage at either side of the ears 21 and at once fix and 80 determine the position of the disc 20 and the plane of the contact carried by it and securely lock said disc against rotative movement. In the case of very large fuses, four 85 ears 21^c, instead of two as just described, are provided on the removable head of the fuse, as shown in Figure 9. In such case the metal tube 18^c is provided with four pairs of lugs 22^c. From the foregoing it is apparent that the removable part of the fuse 90 head 14 comprising the discs 19, 20 and the connected blade 11 is readily removable for the purpose of removing and replacing a fused cartridge and that it is easily and quickly applied with its blade 11 always in 95 the required plane, and that the blade is securely held in that plane by the lugs 22.

The cartridge 13 has a tubular body of insulating material which is closed at its ends by metal tubular caps 24, 25. Each 100 cap is held on the end of the fibre tube by means of its tubular flange gripped against the outside of the tube and a plurality of detents 26 (see Figure 5) punched from the head of the cap and engaged within 105 the end of the tube.

27 indicates the fusible element unit. This consists of two metal plugs 28, 29, which constitute terminals one connected to each metal cap of the cartridge and of a plurality 110

of fusible bars connecting and being supported by said plugs. The plugs 28, 29 are made cylindrical as shown and are provided in their proximate ends with diametric slots 30 to receive the ends of the fusible bars. 31 indicates the fusible bars themselves. As many of said bars 31 are used as are required to carry the load, each bar having a hole 32 to determine its effective cross section in a familiar manner. The bars 31 are arranged in parallel planes with their ends 31^a in juxtaposition and engaged in the slots 30 of the plugs 28 and 29 and with their intermediate lengths 31^b spaced apart as clearly illustrated in Figures 2 and 7. The ends 31^a are riveted in their respective slots 30 by means of rivets 32^a extending diametrically through suitable openings in the plugs and further secured and fixed therein by means of solder. 20 Each plug 28, 29 has a reduced end part 28^x, 29^x which extends through a suitable aperture in the associated cap with the radial shoulder 28^y, 29^y formed by the reduction abutting against the inner face of said cap. 25 Each plug is also provided with a threaded aperture 33 to receive a screw 34 rotatively held in the proximate head of the fuse. The reduced end 28^x of the plug 28 is upset against the outer face of the associated cap 24 of the cartridge (see Fig. 2). An apertured tell-tale-tag plate 35 (see Fig. 5) is engaged on the reduced end 29^x of the plug 29 next to the outer face of the cap 25 and a washer 36, next to the plate 35, and all parts 30 are secured to the plug and to each other by solder. The plate 35 is adapted to extend diametrically across the cap 25 beyond it so that an apertured end 35^a constituting the tell-tale-tag may be bent down against the metal tube 18 on the fuse in advance of the application of the removable head, in position to be engaged and held in place by one of the ears 21. To fix and determine the position of the plate 35, for purposes of assembly, spaced tongues 37 are punched from the cap 25 in position to engage the edges of said plate 35 when in the required position and adapted to be bent down to engage the outer face of said plate. Said tongues are not only 40 of assistance for holding the plate 35 when assembling and soldering the parts but they also act to lock it in position against swinging movement on the end of the plug, after the parts have been attached together. 45 The manner of assembling the cartridge and of inserting or replacing an exploded cartridge will be apparent from the foregoing description. The fusible element 27 is made up in quantities with one, two, three or more fusible bars 31 for various loads. 50 The simplicity of construction of the fusible element and its easy flexibility of adjustment to different loads are manifest. The fusible bars being rigidly connected to the plugs, 28, 29, the fusible element is readily handled as

a unit. The said unit 27 is attached to the cap 24. The fusible unit is then inserted into a cartridge body and the head 24 applied as described. The cartridge is then filled with the familiar powder and the cap 25 is applied to the other end of the body. Preferably a layer of asbestos fibre is placed in the body adjacent each cap as shown in Figures 2 and 3.

After the cap 25 has been applied, with the reduced end 29^x extending beyond said cap, the plate 35 with its tell-tale-tag 35^a is engaged on said reduced end, being first located in position between the lugs or detents 37 in the cap, whereupon said lugs are bent down to hold said plate in place. The washer 36 is next placed upon said reduced end 29^x and solder applied to secure the parts together. The cartridge is now ready and its capacity is shown on the tell-tale tag 35^a. 85

To load the fuse with a cartridge,—the cartridge is inserted in the fuse body and is then rotated until the threaded recess in the plug 28 may be engaged by the screw 34 in the fuse head 15. The screws as has been pointed out, are capable of a rotative movement, but are held in the heads against longitudinal movement,—the screw-heads having flanges which are loosely gripped in a familiar way between the discs comprising the flat heads of the fuse. By means of the aforesaid screw the cartridge is drawn up towards the fuse head 15 until the exposed end of the plug 28 is engaged against the inner face of the fuse head. The fuse head 14 is then applied as already described. 95

The fuse heads and the cartridge caps are provided with vent openings 40, 41 respectively to relieve the pressure generated by the “blowing” of a cartridge. 105

By reason of the construction of fuse units as described, it is possible to manufacture a fuse unit of uniform resistance which will operate on electric circuits successfully in parallel, due to the fact that each fuse in the circuit will take its respective load, so that the load is equally divided between the fuses. 110

I claim as my invention:— 115

1. In an electric fuse, a fusible unit comprising a pair of aligned terminals having threaded apertures in their remote ends, said ends being reduced in diameter, a fusible bar bridging the gap between said terminals and being connected to the proximate ends of said terminals, and a cartridge cap having an aperture through which the reduced end of one terminal extends, a tell-tale tag plate next to said cap provided with an aperture through which said reduced end extends, and a washer on the extreme end of said terminal next to said plate, the several parts being soldered together. 120

2. In an electric fuse, a cartridge having 125

a metallic cap with an aperture at a point located eccentrically therein, a fusible unit including a terminal with a reduced end extending through said cap, a tell-tale tag 5 plate adapted to extend diametrically across said cap and to extend beyond said cap, said plate having an aperture to be engaged on the reduced end of said terminal, and means on said cap for defining the position 10 of said plate.

3. In an electric fuse, a cartridge having a metallic cap with an aperture at a point located eccentrically therein, a fusible unit including a terminal with a reduced end 15 extending through said cap, a tell-tale tag plate adapted to extend diametrically across said cap and to extend beyond said cap, said plate having an aperture to be engaged on the reduced end of said terminal, and 20 lugs stamped out of said cap adapted to de-

termine the position of said plate and to be bent into engagement with its outer face.

4. In an electric fuse, in combination with a tubular body of insulating material and a metal tube fixed on said body and projecting beyond it, a removable head comprising a flat circular head adapted to fit within said metal tube against the end of said tubular body, said circular head being provided with radial extensions having ears extending at right angles to said head and adapted to embrace said metal tube, the projecting end of said tube being provided with notches to receive said radial extensions, and with lugs to engage the 30 edges of said ears.

In testimony that I claim the foregoing as my invention, I affix my signature this 4th day of October, A. D. 1921.

ELMER L. OGLE.
